(57) **CLAIM**

The ornamental design for a shift switch for a motor vehicle, as shown and described.

DESCRIPTION

FIG. 1 is a front perspective view for a shift switch for a motor vehicle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The de-emphasized portions in FIGS. 1-7 illustrate portions of the shift switch for a motor vehicle that form no part of the claimed design. The broken lines in FIGS. 1-7 illustrate the boundaries of the unclaimed areas and also form no part of the claimed design.
